UNITED STATES PATENT OFFICE.

PERCY TRIPP BAILEY, OF MIDDLETOWN, RHODE ISLAND.

FENCE-POST.

1,190,080.

Specification of Letters Patent.

Patented July 4, 1916.

Application filed February 10, 1915. Serial No. 7,380.

To all whom it may concern:

Be it known that I, PERCY T. BAILEY, a citizen of the United States, and a resident of Middletown, in the county of Newport and State of Rhode Island, have invented a new and Improved Fence-Post, of which the following is a full, clear, and exact description.

This invention relates to improvements in posts, and particularly to metallic fence posts, and has for an object the provision of an improved post which in its construction presents an extremely simple, efficient, strong structure.

Another object in view is to provide a metallic post which may be cut out of a sheet of metal and then bent into a proper shape for providing a tapering structure in order that the wire or other fastening material may be properly supported and held in position without danger of sliding or moving under pressure.

In the accompanying drawings—Figure 1 is a front view of a post embodying the invention, the same being shown in position with wires in place; Fig. 2 is an edge view of the structure shown in Fig. 1; Fig. 3 is a section through Fig. 4 on line 3—3; Fig. 4 is a plan view of a piece of sheet metal and several strips or blanks cut therefrom.

Referring to the accompanying drawings by numerals, 1 indicates a blank sheet of metal of any desired kind from which blanks 2, 3 and 4 have been cut. These blanks are all identical in shape, but each alternate blank is reversed, that is, the taper extends in an opposite direction so that only a small waste is allowed, namely, the material in the various spaces 5. From an examination of these blanks it will be observed that the same taper from approximately the point 6 to the upper end 7, and also taper in a reverse direction from point 6 to end 8, end 8 being adapted to enter the earth as shown in Figs. 1 and 2, point 6 being designed to be flush with the ground. When point 6 is flush with the ground the wire engaging face of the post tapers as shown in Fig. 2 from the ground to the top of the post. The taper from point 6 to end 8 allows the post to be easily inserted into the ground and yet provides ample supporting means.

In constructing the blanks, tongues or raised portions 9 are provided on opposite sides. In providing the tongues or raised

portions 9 grooves 10 are also provided, grooves 10 on one side of the post being opposite the raised portion 9 on the opposite side. After the blanks have been cut from the metal they are bent until they present a tapering substantially U-shaped structure in cross section as shown in Fig. 3. This completes the construction of the post. After the post has been placed in the ground as shown in Figs. 1 and 2, the wires 11 forming the fence are caused to engage any of the notches 10 and are tied by suitable tie wires 12 to the post. From Fig. 2 it will be noted that by reason of the taper of the post and the use of the tie wires 12 the upper wires 11 cannot be moved as any tendency for such movement is resisted by the tongues or projections 9, and by the gradual enlargement of the post toward the ground. The various tongues 9 and grooves 10 present a substantially corrugated effect so that wires 11 may be positioned at any point on the post, and also any desired number of wires may be connected to the post. It is evident that not only single strands of wire 11 may be secured to the post but wire mesh or other fencing material may be readily connected to the post without in any way departing from the spirit of the invention. The grooves or wire receptacles 10 extend from the bottom of the post to the top, and thereby allow the use of wire mesh of any kind as well as single strands of wire. The roughened or corrugated portion 12 which extends into the ground acts as means for firmly holding the post when it is in use. In the formation of these posts preferably there are only two operations, namely, the passing of the sheet metal through cutting means, as for instance cutting rollers so as to cut the same in proper shape and then passing these blanks through a bending machine, as for instance tapering bending rollers which act to bend the tapering strips or blanks to a tapering construction U-shaped in cross section. In the opening of the blanks the same are bent so as to produce a taper as shown in Fig. 2, and also a taper as shown in Fig. 1.

What I claim is—

1. A fence post comprising a body formed from a single sheet bent so as to appear in cross section substantially U-shaped, the legs of said U-shaped structure tapering from the top of the post to the bottom so as

to provide a wide supporting base, said legs on their edges also tapering from the ground line to the top of the post in one direction and tapering from the ground line to the bottom of the post in the opposite direction.

2. A fence post, comprising a single body formed from sheet metal bent so as to present a pair of edges, said edges being corrugated, the ridges of the corrugations

of one edge being opposite the grooves of the corrugations of the other edge.

In testimony whereof I have signed my name to this specification in the presence of two subscribing witnesses.

PERCY TRIPP BAILEY.
